UNITED STATES PATENT OFFICE

SCHAMU M. MOSCHCOWITZ AND HERMAN MOSCHCOWITZ, OF NEW YORK, N. Y.

STAY FOR DRESSES, CORSETS, &c.

SPECIFICATION forming part of Letters Patent No. 323,716, dated August 4, 1885.

Application filed July 25, 1883. (No model.)

To all whom it may concern:

Be it known that we, SCHAMU M. MOSCHCOWITZ and HERMAN MOSCHCOWITZ, citizens of the United States, residing at New York, in the county and State of New York, have invented new and useful Improvements in 5 Stays for Dresses, Corsets, &c., of which the following is a specification.

Our invention relates to graduated whalebone stays or auxiliary attachments for such stays; and the novelty consists in the construction and adaptation of the same, as will be more fully hereinafter set forth, and specifically pointed out in the claims.

15 The object of the invention is to provide a stay for corsets or waists, either to be used in connection with whalebones or other stays as auxiliary attachments or independently, which shall be inexpensive of manufacture, efficient and useful in service, readily applied or removed, and susceptible of adjustability as to strength or stiffness. These ends we accomplish in the manner and by the means herein-after described and claimed, reference being 20 had to the accompanying drawings, illustrating the invention, in which—

Figure 1 represents an interior view of one-half of a dress-waist with our invention attached. Fig. 2 is an edge view of two plates connected, showing the method of uniting the same. Fig. 3 is a perspective view of a single plate detached. Fig. 4 is a front and an edge view of a modified form of plate, with devices for connecting the same together. Fig. 5 is a 25 face view and edge view of the clip shown in Fig. 4, detached.

Referring to the drawings, in which similar letters of reference indicate like parts in all the figures, A designates the body of a corset or waist, and B a whalebone or other stay. It is a recognized fault with whalebones that they have no certain spring or strength, being strong but brittle when dry, and weak and unreliable when damp. Continued wearing in a bent position destroys also their capacity to resume their normal straight form. In any of these conditions our invention is a desideratum.

C designates a plate, of spring steel or any 50 other suitable elastic material, having perfor-

rations at each side of each end, as shown at c, and similar perforations, c', arranged opposite each other at a point at a distance from one end of the plate approximating one-third its length. These perforations c and c' are 55 preferably made through ears or slight projections made on the plate, and are adapted to receive the threads by which they are to be sewed to the whalebone-cover or the garment, or by which they are secured together.

In Fig. 2 we show two of the plates secured together in two different arrangements, so as to give a long stay having uniformly diminishing stiffness from the center toward each end, the plates having their longer ends 60 lapped being shown at a, and those having the shorter ends lapping being indicated at b. They are secured together by thread passing through the perforations c' and c, thus producing a long or a short re-enforced plate, 70 as shown. These plates, whether single or double, are shown in Fig. 1 as secured upon the whalebone-stays B at the curve of the waist. This is of importance in many conditions. It allows the wearer to very quickly 75 and conveniently strengthen a weak whalebone at that point. It is a useful auxiliary to a brittle whalebone, and prevents its breaking. In warm weather or climates, where the moistening influence of perspiration is liable 80 to weaken or destroy the resistance of a whalebone, it immediately assumes the strain. The device may be applied directly to the seam of the material or corset or waist, and serves with efficiency without other stays.

In Fig. 3 we show one of the plates, C, in perspective. It will be noticed that the distance from the perforations c in one end to the perforations c' is greater than from the other end to the same point. The plate is thus 90 divided into a short section or portion, 1, and a long portion, 2. In Fig. 2, at a, the plates are lapped over each other upon the parts 2 2, while in Fig. 2, at b, the parts 1 1 are lapped, thus making the difference in length between 95 the two equal to the difference in length between the part 1 and the part 2. This gives a long stay with a gradually-diminishing strength from center to ends, the doubled portion being that part of the curve which accepts 100

the greatest strain. The arrangement shown in Fig. 2, *a*, gives a shorter stay with proportionally greater strength.

From the foregoing it will be observed that 5 the plate C is a convenient stay in any of the relations and conditions cited, and also that it affords a useful auxiliary to any of the stays now in use, and is readily applied.

Instead of making the plate in the form 10 shown in Fig. 3, we may employ the construction shown in Fig. 4, wherein the projections formed laterally, as shown in Fig. 3, are dispensed with, and the ends of the plates are tongued, as shown at *c*², a clip, D, being slipped 15 upon the plates and embracing both. This clip, which is shown in Fig. 5, may be made of metal or other suitable material, and consists of an oblong clip, D, having a longitudinal strip, *d*, which is a very little longer than 20 the width of the plate C, said strip *d* being struck up so that the plate C can be slipped between it and the clip D. Perforations *d*' are formed in each end of the clip, by which 25 it may be secured to the waist or to the sheath of the whalebone-stay. A similar clip, D', may be applied to the tongued ends of the plates C, being of such size that it cannot pass 30 beyond the shoulders at the end of the plate. By such construction the length of the stay may be adjusted to any extent required, and it may be easily secured to the waist. The clip D, which embraces both plates C, being 35 movable in either direction, while the end clips, D', are stationary, the length of the stay may be regulated, as required. If a single plate, C, only is used, the clip D may be allowed to remain thereon in the middle. These plates may be made of steel, of rubber, or of any other suitable material. They may be 40 graduated in width or thickness, and may be made thick in the center and tapering toward the ends.

We are aware that corset-steels have been made adjustable in length, and that they have 45 also been re-enforced by plates permanently riveted thereto at their opposite ends; and such, therefore, we do not claim.

We are also aware that springs composed 50 of two leaves lying upon each other and provided with hooks for attaching and detaching them to and from a corset have been made; but such springs are designed to be used as stays only, and one-half is not adjustable on

the other and provided with fastenings for holding it at various adjustments, so as to 55 regulate the length and resistance of a re-enforce to stays.

We are further aware that one busk has been provided with clips to receive the busk of the opposite side of the corset and with a pin 60 to enter a slot in the latter busk to hold the two parts together; but one is not adjustable upon the other, and provided with fastenings, as in our invention, to regulate the length and resistance of a re-enforce. 65

Having thus described our invention, what we claim is—

1. The combination, with a garment having stays B, of the re-enforce herein described, removable and replaceable from and to the 70 stay at the will of the wearer, composed of elastic plates adjustable one upon the other to vary the length and resistance of the re-enforce, the said plates being provided with fastenings for coupling them together at various 75 points to which they may be adjusted, and also with fastenings for attaching and detaching the re enforce to and from the garment without disturbing the stays of the garment, substantially as described. 80

2. A re-enforce for the stays of garments, removable and replaceable from and to the stay at the will of the wearer, composed of elastic plates adjustable one upon the other to vary the length and resistance of the re-enforce, 85 the said plates being provided with fastenings for coupling them together at various points to which they may be adjusted, and also with the fastenings for detachably securing the plates upon the corset-stay at the waist portion without disturbing the stay, substantially 90 as described.

3. A re-enforce for the stays of garments, composed of elastic plates C, adapted to lie and be adjusted one upon the other and provided each with perforated lateral ears to receive threads to secure them together and to a garment, substantially as described. 95

In testimony whereof we have hereunto set our hands in the presence of two subscribing 100 witnesses.

SCHAMU M. MOSCHCOWITZ.
HERMAN MOSCHCOWITZ.
